Primary Examiner — Michael C Stout*Assistant Examiner* — Katelin G Kloberg(74) *Attorney, Agent, or Firm* — Sanders IP Law(57) **CLAIM**

I claim the ornamental design for a compact playpen, as shown and described.

DESCRIPTION

FIG. 1 is a perspective view of a compact playpen showing my design;

FIG. 2 is a left side elevation view thereof;

FIG. 3 is a right side elevation view thereof;

FIG. 4 is front elevation view thereof;

FIG. 5 is rear elevation view thereof;

FIG. 6 is a top plan view thereof; and,

FIG. 7 is a bottom plan view thereof.

The broken lines depict portions of the article and form no part of the claimed design.

1 Claim, 4 Drawing Sheets
